OTHER PUBLICATIONS

U.S. Appl. No. 29/464,688 of Christopher T. Hardy et al., titled "Human Model" filed Aug. 20, 2013.

Primary Examiner — T. Chase Nelson

Assistant Examiner — Michelle E Wilson

(74) *Attorney, Agent, or Firm* — Saidman DesignLaw Group, LLC

(57) **CLAIM**

The ornamental design for a human model, as shown and described.

DESCRIPTION

FIG. 1 is a perspective view of a human model showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate environmental structure and form no part of the claimed design.
